UNITED STATES PATENT OFFICE.

RAYMOND T. BELL, OF CHICAGO, ILLINOIS.

PENCIL.

Application filed January 9, 1922. Serial No. 527,979.

To all whom it may concern:

Be it known that I, RAYMOND T. BELL, a citizen of the United States, residing at Chicago, in the county of Cook and State of Illinois, have invented certain new and useful Improvements in Pencils, of which the following is a specification.

This invention relates to improvements in pencils of the type in which the lead or crayon is adapted to be fed from the holder as the lead is consumed, and one of the objects of the invention is to improve and simplify the construction thereof and to produce a pencil which will be compact in construction, convenient for use and effective and efficient in operation.

A further object is to provide an improved pencil of this character embodying a cap which is operatively connected with the lead propelling plunger and by means of the rotation of which cap the plunger is actuated, and improved means for securing the cap to the barrel or sheath of the pencil for rotation with respect thereto, and at the same time to provide improved means whereby the cap may be readily removed without danger of straining or injuring any of the parts.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which—

Figure 1 is a view in elevation.

Figure 2 is an enlarged detail vertical sectional view taken on line 2—2, Figure 1.

Figure 3 is a horizontal sectional view taken on line 3—3, Figure 2.

Figure 4 is a horizontal sectional view taken on line 4—4, Figure 2.

Figure 5 is a top plan view of Figure 6.

Figure 6 is a side elevation of Figure 5.

Figure 7 is a top plan view of Figure 8.

Figure 8 is a side elevation of Figure 7.

Referring more particularly to the drawing the numeral 15 designates the sheath or body of the pencil, which may be of any desired size and configuration and constructed of any suitable light material.

The sheath 15 is provided with a central bore 16 extending throughout the length thereof, and operating in the bore is a lead

propelling plunger 17, which is operatively connected with a propelling member or screw 18.

Secured to one end of the sheath is a tip 19 and the other end of the sheath is reduced as at 20 to form a shoulder 21. Encompassing this reduced portion 20 is a sleeve 22, constructed of any suitable material, such as metal or the like. This sleeve 60 fits snugly upon the sheath and is provided with diametrically opposite laterally projecting lugs 23 intermediate the ends thereof. Encompassing the sleeve 22 is another sleeve 24, and this sleeve 24 is provided with 65 diametrically opposite bayonet slots extending through the lower edge of the sleeve as at 25, the portion 26 of the slot being of any desired length.

This sleeve 24 is adapted to be held in 75 position about the sleeve 22 by positioning the open ends 25 of the bayonet slots so that the lugs 23 on the sleeve 22 will enter thereinto and after the sleeve 24 has been adjusted so that the lugs will stand adjacent the portion 26 of the bayonet slot the lugs will enter that portion of the slot when the sleeve 24 is rotated with respect to the sleeve 22.

The sleeve 24 is also provided with a circumferentially reduced portion 27 intermediate its ends and above the bayonet slot, the external diameters of the sleeves 22 and 24 are less than the external diameter of the sheath 15 beyond the reduced portion. 85 90

A cap member 28 is adapted to extend over the sleeve 24 and also the adjacent extremity of the sheath 15. This cap member 28 is provided with a sleeve portion 29, having a spring tongue 30 cut therefrom, 95 and the tongue is deflected inwardly into the sleeve portion 29 as shown more clearly in Figure 3. This spring tongue 30 is provided as a means for frictionally and yieldingly locking the cap 28 upon the end of the sheath and co-operates with the sleeve 24 for locking the cap to the end of the sheath. When the cap 28 is placed in position so that the tongue 30 enters the circumferential recess 27 of the sleeve 24, and 100 which tongue is preferably of a width slightly less than the width of the circumferential recess 27, the sleeve 24 and cap will be locked together and the sleeve 24 is locked with the sleeve 22 by means of the lugs 23 and bayonet slots in the sleeve 24. 110

The operating screw 18 for the plunger

17 is connected with the cap 28 as at 31 for rotation with the cap so that as the cap is rotated the screw 18 will be actuated and this will cause the plunger 17 to move forwardly or backwardly in directions lengthwise of the sheath of the pencil in accordance with the direction of rotation of the cap.

When the cap 28 is rotated the frictional contact between the spring tongue 30 and the bottom of the annular recess 27 in the sleeve 24 will cause the latter to rotate with the cap until the lugs 23 on the sleeve 22 engage one or the other of the ends of the horizontal portion of the bayonet slot according to the direction of rotation of the cap and by exerting a pressure upon the cap so as to hold the same against the end of the sheath the sleeve 24 will, when the lugs 23 engage the end of the slot be arrested in its rotation and the cap 28 may then be rotated with respect to the sleeve 24. When it is desired to remove the cap it is rotated so that the lugs 23 will stand adjacent the portion 25 of the bayonet slot in the sleeve 24, after which the cap may be readily removed and with it the sleeve 24 by moving the same in a direction longitudinal of the shaft and away from the sheath.

The cap may be readily applied by reversing this operation.

With this improved construction it will be manifest that the cap may be readily applied or removed without in any manner injuring or damaging any of the parts of the mechanism.

Obviously and if desired additional tongues 30 may be employed.

While the preferred form of the invention has been herein shown and described it is to be understood that various changes may be made in the details of construction and in the combination and arrangement of the several parts, within the scope of the claims, without departing from the spirit of this invention.

What is claimed as new is:—

1. A pencil embodying a sheath, a collar secured about one end thereof, one or more laterally projecting lugs on the collar, a second collar encompassing the first recited collar and provided with bayonet slots opening through one end to receive the said lugs for rotatably and detachably securing the second recited collar, a cap for the end of the sheath, a portion of the cap encompassing the second recited collar, means securing the cap to the second recited collar for rotation therewith and with respect thereto, and a lead or crayon projecting element within the sheath and secured to the cap for rotation therewith.

2. A pencil embodying a sheath, a collar secured about one end thereof, one or more

laterally projecting lugs on the collar, a second collar encompassing the first recited collar and provided with bayonet slots opening through one end to receive the said lugs for rotatably and detachably securing the second recited collar, a cap for the end of the sheath, a portion of the cap encompassing the second recited collar, means frictionally securing the cap to the second recited collar for rotation therewith and with respect thereto, and a lead or crayon projecting element within the sheath and secured to the cap for rotation therewith.

3. A pencil embodying a sheath, a collar secured about one end thereof, one or more laterally projecting lugs on the collar, a second collar encompassing the first recited collar and provided with bayonet slots opening through one end to receive the said lugs for rotatably and detachably securing the second recited collar, a cap for the end of the sheath, a portion of the cap encompassing the second recited collar, inter-engaging portions between the cap and the second recited collar for securing them for rotation together and also for rotation one with respect to the other, and a lead or crayon projecting element within the sheath and responsive in its operation to the operation of the cap.

4. A pencil embodying a sheath, a collar secured about one end thereof, one or more laterally projecting lugs on the collar, a second collar encompassing the first recited collar and provided with bayonet slots opening through one end to receive the said lugs for rotatably and detachably securing the second recited collar, a cap for the end of the sheath, a portion of the cap encompassing the second recited collar, means securing the cap to the second recited collar for rotation therewith and with respect thereto, and a lead or crayon projecting element within the sheath and secured to the cap for rotation therewith, the said means embodying a spring tongue on the cap and a circumferential groove in the face of the second recited collar adjacent the cap and into which groove the said tongue projects.

5. A pencil embodying a sheath, a cap rotatably and detachably connected with one end of the sheath, a collar exterior of the sheath and disposed between the cap and the sheath, means rotatably and detachably securing the collar to the sheath, a lug and bayonet slot connection for securing the cap and collar for rotation together and also one with respect thereto, and a lead moving element within the sheath and responsive in its operation to the actuation of the cap.

6. A pencil embodying a sheath, a cap rotatably and detachably connected with one end of the sheath, a collar disposed between the cap and the sheath, means rotatably and detachably securing the collar to the sheath,

- means securing the cap to the collar for rotation therewith and with respect thereto, the last recited means embodying a circumferential peripheral recess in one of the parts 5 and a spring tongue on the other part projecting into the said recess, and a lead moving element within the sheath and responsive in its operation to the actuation of the cap.
- 10 7. A pencil embodying a sheath, a cap rotatably and detachably connected with one end of the sheath, a collar disposed between the cap and the sheath, means rotatably and detachably securing the collar to the sheath, 15 the said means embodying one or more laterally projecting lugs on one of the parts and bayonet slots on the other part for receiving the lugs, means securing the cap to the collar for rotation therewith and with respect 20 thereto, and a lead moving element within the sheath and responsive in its operation to the actuation of the cap.
8. A pencil embodying a sheath, a cap into which one end of the sheath projects, 25 said cap being rotatably mounted upon the end of the sheath, a collar encompassing the end of the sheath, said collar extending into the cap, a lug and bayonet slot connection between the cap and the collar, and means 30 within the sheath and responsive in its operation to the rotation of the cap with respect
- to the sheath for projecting the lead or crayon from the sheath.
9. A pencil embodying a sheath, a cap for one end thereof, a collar exterior of the 35 sheath, means frictionally and detachably connecting the cap and collar and for securing them for rotation together and also for rotation one with respect to the other, and a lug and bayonet slot connection between the collar and sheath for detachably securing the collar to the sheath, the said connection operating to permit a limited degree of rotation of the collar with respect to the sheath while the parts are being secured together. 40
10. A pencil embodying a sheath, a collar secured about one end thereof, a laterally projecting lug on the collar, a second collar encompassing the first recited collar and 50 provided with a bayonet slot opening through one end to receive the said lug for rotatably and detachably securing the second recited collar, and a lead or crayon projecting element within the sheath and connected with the said second collar for rotation therewith. 55

In testimony whereof I have signed my name to this specification, on this 19th day of December, A. D. 1921.

RAYMOND T. BELL.
